UNITED STATES PATENT OFFICE.

MÉHUL COPET-HARDENNE, OF PONDROME, BELGIUM.

SCALING DEVICE.

983,875.

Specification of Letters Patent. Patented Feb. 14, 1911.

Application filed July 9, 1910. Serial No. 571,187.

To all whom it may concern:

Be it known that I, MÉHUL COPET-HARDENNE, a subject of the Belgian King, and residing at Pendrome, Belgium, have invented new and useful Improvements in Scaling Devices; and I do hereby declare the following to be a full, clear, and exact description of the same.

The object of my present invention is to provide an improved device for climbing up trees and the like and more particularly a device comprising two extensible belts arranged a certain distance above each other and intended to be passed around the tree or the like, the upper belt carrying two stirrups suspended from the same by means of straps and a seat also suspended by means of straps, while the lower belt has two fixed stirrups, for the purpose of affording the greatest possible convenience during the operation.

My invention will be readily understood from the following description taken in connection with the accompanying drawings, wherein:

Figure 1 is the front elevation of the climbing device; Fig. 2 is the top plan view of the upper belt passed around a tree, Fig. 3 is the top plan view of the lower belt passed around a tree and Fig. 4 is a perspective view of the complete apparatus in operative position.

My present climbing device is composed of two belts 1, 2 made of flexible material such as leather or the like and formed of two parts adapted to slide on each other. These two parts of each belt serve to extend or contract the latter according to the diameter of the tree; after adjusting the belts, the parts thereof are secured together by means of a suitable clip 3. Of course, the belts 1, 2, may also be extended or contracted by other suitable means, without departing from the scope of the invention. The two belts are connected together by means of two or more straps 4, attached to the upper belt and fastened to the lower belt with buckles 5 or the like. Each belt has at one end a metal strip 6, on which is journaled a lever 7 provided with a pro-

jecting pin 8, and at its opposite end a hinge 9 to which is pivoted a bar 10 provided with notches or teeth, adapted to be engaged by the pin 8 when the lever 7 and bar 10 are moved toward each other for tightening the belt around the tree. The lever 7 is normally held out of operation by a hook 11 attached to the belt. The upper belt is provided with two straps 12, 12 each of which carries a stirrup (not shown in the drawings), and two other straps 13, 13 carrying a seat (not shown) for the operator. The lower belt is provided with two fixed stirrups 14.

In order to climb up a tree or the like, the operator attaches the two belts at a certain height of the tree and climbs up the latter until he reaches the upper belt 1, whereupon he places his feet into the stirrups of the straps 12 and loosens the lower belt 2 to raise and fasten the same near the upper belt. Now the operator places his feet upon the fixed stirrups 14 of the lower belt, loosens the upper belt 1, fastens the same higher up, places his feet again upon the stirrups of the straps 12 and then fastens the lower belt 2 higher up. The operator repeats this operation until he reaches the desired height whereupon he places himself upon the seat for working. The climbing device described may also be provided with a safety-belt for the purpose of preventing the operator from falling down by want of attention.

It will be easily understood that my improved device enables even non-skilled men to easily climb up any tree, the said device not injuring in the least the bark of the tree.

Having fully described my invention, what I claim and desire to secure by Letters Patent is:—

An improved scaling device, comprising in combination two extensible belts made of flexible material and adapted to be clamped or tightened around trees, the one above the other, two adjustable straps connecting the upper belt to the lower belt, two straps adjustably connected at their upper ends to the upper belt, stirrups secured

to the lower free ends of the last mentioned straps, a pair of stirrups secured to the lower belt at a suitable distance apart from each other, a pair of straps attached to the upper belt, and a suitable seat carried by these straps, substantially as and for the purpose set forth.

In testimony whereof, I have signed my name to this specification in the presence of two subscribing witnesses.

MÉHUL COPET-HARDENNE.
